H. ROSS.

Puddling-Furnaces.

N° 73931

Patented Jan. 28, 1868.

Attest;

James J. Johnston
A. C. Johnston

Inventor, Henderson R

United States Patent Office.

HENDERSON ROSS, OF PITTSBURG, PENNSYLVANIA.

Letters Patent No. 73,981, dated January 28, 1868.

IMPROVEMENT IN PUDDLING-FURNACES.

The Schedule referred to in these Letters Patent and making part of the same.

TO ALL WHOM IT MAY CONCERN:

Be it known that I, HENDERSON ROSS, of Pittsburgh, in the county of Allegheny, in the State of Pennsylvania, have invented a new and useful Improvement in Furnaces; and I do hereby declare that the following is a full and exact description thereof, reference being had to the accompanying drawings, and to the letters and figures of reference marked thereon.

The nature of my invention consists in providing a furnace with a detached metallic "clamp" furnished with a water-chamber. My invention also consists in providing the furnace with a metallic neck or throat, and stack or chimney, said neck and stack being furnished with water-chambers, the whole being constructed, arranged, and operating, substantially in the manner and for the purpose hereinafter described.

To enable others skilled in the art to make and use my invention, I will proceed to describe its construction and operation. In the accompanying drawings, which form part of my specification—

Figure 1 is a longitudinal section of my improvement in neck and stack of an ordinary puddling-furnace.

Figure 2 represents a transverse section of the stack when cut through at line x' of fig. 1.

Figure 3 represents a transverse section of the neck of the furnace when cut through at line x of fig. 1.

In the drawings, A represents the detached metallic "clamp," which is provided with a water-chamber marked m . B represents the lower part of the stack or chimney, furnished with a water-chamber, n , and a door, D, the width of the door being equal to the breadth of the neck of the furnace. C represent the sides of the neck, which are provided with water-chambers, o , which are connected with the water-chambers n of the stack. The water-chambers of the "clamp," neck, and stack must be provided with suitable pipes for supplying them with water, and also pipes for carrying off the heated or "waste water." The arrangement of these supply and waste-pipes, and the means for cleaning out the water-chambers, I leave to the skill and judgment of the mechanic. The dotted lines in fig. 1 are used for the purpose of showing the relation of my improvement to the balance of the furnace. 1 represents the crown of the furnace, 2 represents the bridge-wall, 3 represents the grate-bars, 4 represents the bottom plate, 5 represents the bosh, and 6 represents the form of the bottom of the neck, all of which are constructed in the usual manner and with the ordinary material. The back end, and that portion of the crown of the furnace directly over the fire-chamber x^2 , I propose making of iron, and furnishing it with a water-chamber, as indicated by the dotted lines marked x^3 , which device I propose making the subject of another application for Letters Patent, and therefore will not at present further describe it. The upper part of the stack of the furnace may be constructed of brick or iron, with the bottom course of fire-brick lining resting on the offset marked e , shown in fig. 1, or the whole stack may be constructed with the chamber n extending from the bottom to the top of it. The door D is provided with a flange, i , for supporting and holding brick lining. This door is used for the purpose of affording a ready opening for cleaning out the neck or throat of the furnace. The form, size, and the manner of constructing the several parts of my improvement, I leave to the judgment of the mechanic. It will readily be observed that the sides C and clamp A may be so constructed as to form one part, with a single water-chamber, therefore I do not confine my invention to making the neck or throat of the furnace in several parts.

The operation of my improvement is as follows: Water is conveyed into the different chambers at the lowest point, and carried off at the highest point. By thus supplying and carrying off the water, the chambers will always be kept full of cool water. The stack B, with its chamber n , may be used for generating steam, which may be utilized for any desired purpose.

The advantages of my improvement consist in saving brick, time, and cost of repairing the neck of the furnace. The action of the furnace when provided with my improvement will always be uniform, which is a very great desideratum, and especially so in furnaces used for the manufacture of iron and steel.

Having thus described the nature, construction, operation, and advantages of my improvement, what I claim as of my invention, is—

1. A water-clamp for furnaces, constructed, arranged, and operating substantially as herein described and for the purpose set forth.
2. Surrounding the neck or throat with water, substantially as herein described and for the purpose set forth.

Witnesses:

H. E. DAVIS,

JAMES J. JOHNSTON.

HENDERSON ROSS.
